(57) **CLAIM**

The ornamental design for a vacuum insulated flask, as shown and described.

DESCRIPTION

1. Vacuum insulated flask

1.1 : Bottom

1.2 : Top

1.3 : Right

1.4 : Perspective

1.5 : Front

1.6 : Back

1.7 : Perspective

1.8 : Left

The parallel thin lines in the representation represent contours only and do not illustrate an ornamentation or decoration on the surface of the product.
